SWITCH CONTROL APPARATUS

Filed July 19, 1926

UNITED STATES PATENT OFFICE

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

SWITCH-CONTROL APPARATUS

Application filed July 19, 1926. Serial No. 123,336.

This invention relates to train operated switches. It is the object of this invention to provide roadside and train carried apparatus for the operation of siding switches and the like.

Another object of the invention is to provide such devices with manually controllable apparatus so that the trainman may open or close the switches as desired.

10 Another object of the invention is to provide for the operation of such devices in such a manner that they become inoperative when the train exceeds a certain maximum speed.

15 The above objects are accomplished by providing a switch operating mechanism which is controlled by roadside devices. The roadside devices are so designed that they may cause the operation of the mechanism either to open or to close the switch.

20 The switch operating mechanism is usually electrically operated and its energy is usually furnished by a battery. In the system illustrated in the present application the 25 roadside devices control the connection between the battery and the switch operating mechanism in such a manner that the battery may be applied to the mechanism in either of two reverse directions.

30 These roadside controlling devices in their turn are controlled by train carried devices. The train carried devices may be operated so as to bring about the opening of the switch or the closing of the switch.

35 The roadside along the main track is provided with a ramp at a desired distance from the switch and its siding is provided with a similar ramp. The first ramp is designed to cooperate with devices carried on the

40 tender of the train while the second ramp is adapted to cooperate with devices carried on the caboose or last car of the train. While in the operation and use of the system the devices on the tender are intended

45 to close the switch and the devices on the caboose are intended to open the switch, it will be apparent that these devices may operate in any desired manner.

50 In the drawings:

Figure 1 is a diagrammatic showing of the roadside devices; and

Figure 2 is a diagrammatic showing of the train carried devices.

The train carried apparatus shown in Figure 2 of the drawings is duplicated on the train. One installation is on the tender and the duplicate installation is on the caboose or last car of the train. The first installation is manipulated when the train 55 approaches a siding and it is desired to shift the switch to its reverse position so as to permit the train to enter the siding. The same apparatus may sometimes be utilized for shifting the switch to normal should 60 the switch be left in its reverse position inadvertently. The installation on the caboose is used to shift the switch to normal after a train has entered the siding.

The train carried apparatus comprises a 70 shoe S adapted to make contact with the ramp R. The shoe S carried by the stem 1 is normally in such a position that it may pass over any ramp without touching same. When the train has to enter a siding, the 75 engineman may cause the shoe stem 1 to be projected downwards so that the shoe S may contact with the ramp R. This is accomplished by the operation of the valve V which permits the compressed air of the air 80 brake system to enter the chamber C and slidably move the shoe stem 1 against the action of a spring (not shown). The air pipe P between the valve and the cylinder is provided with the whistle W, which will 85 blow until the valve V is again placed in its normal position. The whistle then serves as a vent for the compressed air in the cylinder C and the spring will then retract 90 the stem and shoe to their normal position.

When the movable stem 1 is in its projected position the contact knives 4 and 13, which are rigidly mounted on the stem 1, are brought into bridging position with the contacts 3 and 5 and 12 and 14 respectively. The speed controller SC is provided with a contact bridge 8 which serves as a bridge for the wires 6 and 16 when the speed is 95 below a certain maximum.

With the pole changer PC in the position shown and with the movable stem 1 in its extended position, the positive side of the battery B is connected to ground through the pole changer PC, conductors 2, 3, 4, 5, 6, speed controlled contact 8 and 16 to ground. The negative side of the battery B is connected to the shoe S through pole changer PC, conductors 17, 11, 12, 13, 14, 15 and the shoe S. Under these conditions, therefore, the battery is grounded or connected to the track on the positive side and connected to the shoe on the negative side.

When the operator of a train desires to enter the siding, he opens valve V in the air pressure line P which causes the projection of the shoe S to such a position that as the train passes the ramp R the shoe will come in contact with the ramp R. The circuit above traced connecting the negative side of the battery B and the shoe S then proceeds through the ramp R, line 30, electromagnet 22, winding 31 of the rotatable element 20, wire 32, contact 33, wire 34, back to the track where it is completed through G, 16, speed controlled contact 8, and elements 6, 5, 4, 3, 2, PC and back to the positive side of the battery.

The elements 20 to 31 inclusive constitute a diagrammatic showing of the indicator selector described in Patent No. 1,527,465. The elements 20 and 24 are integrally connected as shown by the dotted line 85. The element 20 is disposed between the poles of the permanent magnet 21. The elements 20 and 24 are held normally in the position shown by the engagement of the lug on armature 23 with a cooperating notch in the periphery of 24.

When due to the circuit traced above the electromagnet 22 is energized, the lug on the armature 23 is withdrawn from the notch in 24 and the elements 20, 24 are free to move. The direction of rotation of 20, 24 will depend upon the direction of flow of current in winding 31 and the spatial relation between the winding and the poles of the magnet 21. Let us assume that the energization of the winding 31 by a current from left to right will cause the rotation of 20 in the clockwise direction and a current in 31 from right to left will cause the rotation of 20 in the counter clockwise direction. Under the conditions therefore existing at this point in the operation of the system, with the positive side of the battery connected to ground the elements 20, 24 will rotate in the counter clockwise direction. The contact elements 27, 28, 29 rotate with 20 and will therefore assume the dotted line position indicated by c.

The closing of contacts 28, 29 to the c position will close the following circuit: positive side of battery B1, conductors 50, 55, 52, switch operating mechanism SM;

51, 54, 29 and 53 back to the battery. This will energize the switch operating mechanism and it will operate to move the railroad switch SR from its normal to its reverse position.

The operation of the switch operating mechanism is such that in the first step the lock bolt 71 is withdrawn from the lock rod 70. This releases the spring contact 41 and permits it to come in contact with the fixed contact 81. The following circuit is thereby established: positive side of battery B1, wire 40, contacts 81, 41, 42, conductor 43, contact 27 in its c position, wire 44, winding 26 of the electromagnetic clutch mechanism, and wire 45 back to negative side of battery. The electromagnetic clutch is thereby polarized and serves to hold the armature stop 25 in its dotted c position and thereby the contacts 27, 28, and 29 will be retained in their operative position. This makes it possible for the switch operating mechanism SM to complete its operation of the railroad switch SR after the shoe S has passed the ramp R. The ramp R is long enough so that the energization of winding 31 is long enough to permit the operation to proceed to the point where the contacts 27, 28 and 29 assume their c positions followed by the closing of the contacts 41, 81. The stick circuit of the winding 26 will now hold the battery B1 properly connected to SM and the operation of SM will proceed without the aid of the train carried devices. The train carried devices are utilized merely to initiate the operation of the wayside devices. The completion of the operation of shifting the railroad switch is independent of the train carried devices.

When the switch operating mechanism SM has completed the shifting of the railroad switch, the lock bolt 71 will again enter an aperture in the lock rod 70 and thereby lock the railroad switch against possible displacement. At the end of this operation the contacts 41, 81 will again be disengaged; the circuit just traced for the winding 26 will be broken and the stop 25 will be free to move and together with the element 20 will rotate back to its normal position as indicated in the drawing.

83 indicates a semaphore signal whose operation is controlled in a well known manner by means of a block signaling circuit, part of which only is indicated in the drawings in the partial circuit 62, 63, 46, 64, control relay CR and 65. The control relay controls the operation of the semaphore signal 83. In the system shown herein the block signaling system is made to cooperate with the switch operating system in that a switch SB is inserted in the block signaling circuit, which switch is operable by the shifting of the railroad switch. When the

latter has reached its reverse position the switch SB is opened, and the semaphore 83 is operated to indicate to the engineman that the switch has been shifted and that the train may proceed to the siding.

5 When the train enters the section X, the consequent deenergization of TX is accompanied by the opening of contacts 42 and 33 and their respective circuits, with the consequent return of contacts 27, 28, 29 to normal. 10 This serves to prevent the shifting of the railroad switch under the train.

On the left side of the siding is provided a ramp R' which corresponds to the ramp R. 15 The closing of the railroad switch is effected by the operation of devices shown in Figure 2 that are carried by the tender and are under the control of the engineman. The caboose or the last car of the train carries a similar device and its shoe is disposed 20 on the left side of the train. This device on the caboose is intended to cooperate with the same wayside system by means of the ramp R' and is intended to effect the opening 25 of the switch or to return it back to its normal position. The devices on the caboose are in the same position as shown in Figure 2. The train conductor operates the valve V after the last car of the train has 30 entered the siding and the shoe S which is connected to the negative side of the battery B is brought in contact with the ramp R'. The circuit is now completed from the ramp R' through 60, contact 33, wire 32, 35 winding 31, magnet 22, wire 61, back to the siding and through the remainder of the train carried circuit. It will be seen that in 40 this circuit the connection of the battery B with relation to 31 is in the reverse direction as compared with the circuit as traced during the operation of the switch mechanism to close the switch. The element 20 will therefore now rotate in the clockwise direction and the stop 25 will abut against the 45 clutch element 84 and the contacts 27, 28 and 29 will assume the dotted a positions. The switch operating mechanism will now be connected in the following circuit: battery B1, wires 50, contact 28, wire 51, SM, 50 52, 29 and 53 back to the battery. The battery B1 will now be connected in the reverse direction as compared with the connection that takes place when the switch is being closed. The switch operating mechanism 55 will therefore operate in the reverse direction and the switch will be opened or be returned to normal. The function of the contacts 81 and 41 controlled by the operation of the lock bolts 70 and 71 remains the 60 same as in the other operations.

While I have shown a shoe and ramp arrangement of transmitting energy from the train carried devices to the wayside devices, I do not wish to be limited to this manner 65 of operating. Any one of a number of

other means known in the art may be utilized in place of the shoe and ramp arrangement, such as inductive devices, magnetic devices and others.

The elements 20 to 31 constitute a dia- 70 grammatic showing of an indication selector fully described in Patent No. 1,527,465. However I do not wish to be limited to this specific form of a controlling device for controlling the operation of the switch.

A light L is inserted in the train carried circuit between the grounded side of the speed responsive device and one side of the battery in such a manner that its circuit is as follows: battery, pole changer, wire 17, 80 lamp L, switch controlled contact 8, wire 6, 5, 4, 3, 2, pole changer and back to battery. The operation of this lamp will therefore be controlled by the speed controlled device and will serve as an indication to the train- 85 man whether or not he is exceeding the speed limit under which the switch operating system is supposed to operate.

While I prefer to operate this system with a speed controlled device and prevent its 90 operation when a certain maximum speed is exceeded, the system may also be operated without such a speed controlled device by inserting the ground connection at a point G' as indicated in dotted lines. The installation on the caboose need not be provided 95 with a speed controlled device.

In case a train passing from left to right should find the switch set in its reverse position the trainman may reset it back to 100 normal by shifting the pole changer PC to its dotted line position and projecting the shoe S.

It will be seen from the above that the present system provides means whereby a 105 train operator may shift the railroad switch without stopping the train by a momentary transfer of energy from train carried devices to roadside devices; that by the momentary transfer the operation of the roadside de- 110 vices is initiated and that the operation pro- 115 ceeds and is completed without the aid of the train carried devices; and that the switch cannot be moved from its normal position to its reverse position unless the train is moving at a speed below a predetermined maximum.

I, however, do not wish to be limited to the system and devices disclosed herein, for 120 many changes and modifications may be made without departing from the spirit of the invention defined in the following claims.

What I claim is:

1. A railroad switch operating system 125 comprising a switch operating mechanism, a source of energy for energizing the mechanism, a device controlling the application of the source to the mechanism, and speed 130

- responsive train carried means for controlling the operation of the device.
2. A railroad switch operating system comprising a switch operating mechanism operable to open or close the switch, a selective device controlling the direction of operation of the mechanism, and speed responsive train carried means for controlling the operation of the device.
3. A railroad switch operating system comprising speed responsive train carried means and wayside means cooperating with said first means to operate the switch.
4. A railroad switch operating system comprising speed responsive train carried means, wayside means adapted to cooperate with said first means to operate the switch, and manual means for controlling the operation of the system.
5. A railroad switch operating system comprising speed responsive train carried means, wayside means adapted to cooperate with said first means to operate the switch and manually controlled means associated with said first means for controlling the operation of the system.
6. A railroad switch operating system comprising speed responsive train carried means, wayside means adapted to cooperate with said first means to operate the switch and manually controlled means associated with said first means for making said first means effective or ineffective as desired.
7. A railroad switch operating system comprising a switch operating mechanism, normally unenergized wayside devices for controlling the operation of said mechanism, and manually controllable train carried means for selectively energizing said devices with energy of either one characteristic or an opposing characteristic.
8. A railroad switch operating system comprising a switch operating mechanism for opening and closing the switch, wayside means for controlling the direction of operation of the mechanism, train carried means for selectively operating said last named means in either one of two ways and means for maintaining said wayside means in its operative position.
9. A railroad switch operating system comprising a switch operating mechanism for opening and closing the switch, means for controlling the direction of operation of the mechanism, manually controllable train carried means for selectively operating said direction controlling means, means for maintaining said last named controlling means in one of its operative positions.
10. A railroad switch operating system comprising a switch operating mechanism for opening and closing the switch, means for controlling the direction of operation of the mechanism, means for maintaining said last named controlling means in one of its operative positions, and means controlled by the switch operating mechanism for deenergizing the last named means.
11. A railroad switch operating system comprising an electro-responsive device on the wayside, means partly disposed on the wayside and partly carried by the train for selectively energizing said device, and means whereby the energization of said device in one direction will effect the opening of the switch and the energization of said device in the opposite direction will effect the closing of the switch.
12. A railroad switch operating system comprising a switch operating mechanism for opening and closing the switch, a rotatable element capable of rotation in two directions, means partly disposed on the wayside and partly carried by the train for selectively operating said element, and means whereby the rotation of said element in one direction will influence the switch operating mechanism to open the switch and the rotation of the device of the element in the opposite direction will influence the switch operating mechanism to close the switch.
13. The combination of a railroad switch operating mechanism and means for controlling the operation of said mechanism comprising a polarized electro-responsive device capable of rotation in two directions whereby energy may be applied to said mechanism for operating it in either of two directions, clutch means for holding said polarized device in one of its operative positions and means whereby the clutch device is maintained in its inoperative position at the beginning of the operation of the mechanism.
14. The combination of a railroad switch operating mechanism for opening and closing a railroad switch, a movable electro-responsive element capable of assuming one inoperative position and two operative positions, means whereby the mechanism will operate to open the switch when said electro-responsive device is in one of its operative positions and whereby the mechanism will operate to close the switch when said device is in the other of its operative positions, means whereby the said electro-responsive device is normally maintained in its inoperative position, clutch means whereby the said device is maintained in one of its operative positions during the operation of the mechanism, and means whereby the clutch means is maintained inoperative at the beginning and at the end of the operation of said mechanism.
15. The combination of a railroad switch operating mechanism and means for controlling the operation of said mechanism comprising a polarized electro-responsive device capable of rotation in two directions whereby energy may be applied to said

- mechanism for operating it in either of two directions, clutch means for holding the polarized device in one of its operative positions, and means whereby the clutch device is maintained in its inoperative position at the end of the operation of the mechanism. 5
16. The combination of a railroad switch operating mechanism and means for controlling the operation of said mechanism comprising a polarized electro-responsive device capable of rotation in two directions whereby energy may be applied to said mechanism for operating it in either two directions, clutch means for holding the polarized device in one of its operative positions, and means whereby the clutch device is maintained in its inoperative position at the beginning and at the end of the operation of the mechanism. 10
17. The combination of a railroad switch operating mechanism and means for controlling the operation of said mechanism comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit controlled by the switch operating mechanism. 20
18. The combination of a railroad switch operating mechanism and means for controlling the operation of said mechanism comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit and means whereby said switch is controlled by the operation of the switch operating mechanism. 30
19. The combination of a railroad switch operating mechanism and means for controlling the operation of said mechanism comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit, said switch being normally open and means whereby the switch is closed after the beginning of the operation of the switch operating mechanism. 50
20. The combination of a railroad switch operating mechanism and means for controlling the operation of said mechanism comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit, said switch being normally open and means whereby said switch is closed after the beginning of the operation of the switch operating mechanism. 55
- device capable of rotation in two directions whereby energy may be applied to said mechanism for operating it in either of two directions, an electro-responsive clutch device for holding said polarized device in one of its operative positions, a circuit for said clutch device and a switch in said circuit, said switch being normally open and means whereby said switch is closed after the beginning of the operation of the switch operating mechanism. 70
21. In a railroad switch operating system, the combination of a switch operating mechanism, roadside devices for maintaining said mechanism energized throughout a shifting movement of the switch and speed controlled train carried devices cooperating with said roadside devices for initiating the operation of the mechanism. 80
22. A railroad switch operating mechanism of the type having a lock bolt for locking the switch in its normal and in its reverse positions, in combination with a source of energy, train controlled means for applying the source of energy to said mechanism in either one of two ways, and means controlled by the locking movement of the lock bolt for disconnecting the source of energy. 90
23. A railroad switch operating mechanism of the type having a lock bolt for locking the switch in combination with a source of energy, electro-responsive means for applying the source of energy to the mechanism, an electro-responsive clutch device for holding said energy applied to the mechanism, and a switch in circuit with said clutch device operable by the operation of said lock bolt. 100
24. A railroad switch operating mechanism of the type having a lock bolt for locking the switch in combination with a source of energy, electro-responsive means for applying the source of energy to the mechanism, an electro-responsive clutch device for holding said energy applied to the mechanism, and a switch in circuit with said clutch device operable to closed position by the unlocking movement of the lock bolt. 110
25. A railroad switch operating mechanism of the type having a lock bolt for locking the switch in combination with a source of energy, electro-responsive means for applying the source of energy to the mechanism, an electro-responsive clutch device for holding said energy applied to the mechanism, and a switch in circuit with said clutch device operable to open position by the locking movement of the lock bolt. 115
26. A railroad switch operating mechanism of the type having a lock bolt for locking the switch in combination with a source of energy, electro-responsive means 120
- comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit, said switch being normally open and means whereby the switch is closed after the beginning of the operation of the switch operating mechanism. 125
- comprising a polarized electro-responsive device capable of rotation in two directions whereby energy may be applied to said mechanism for operating it in either of two directions, an electro-responsive clutch device for holding said polarized device in one of its operative positions, a circuit for said clutch device and a switch in said circuit, said switch being normally open and means whereby the switch is closed after the beginning of the operation of the switch operating mechanism. 130

for applying the source of energy to the mechanism, train carried means for initially energizing said electro-responsive means, an electro-responsive clutch device for holding said energy applied to the mechanism, and a switch in circuit with said clutch device operable by the operation of said lock bolt.

27. A railroad switch operating mechanism of the type having a lock bolt for locking the switch in combination with a source of energy, electro-responsive means for applying the source of energy to the mechanism, train carried means for initially energizing said electro-responsive means, an electro-responsive clutch device for holding said energy applied to the mechanism, and a switch in circuit with said clutch device operable to closed position by the un-locking movement of the lock bolt.

28. A railroad switch operating mechanism of the type having a lock bolt for locking the switch in combination with a source of energy, electro-responsive means for applying the source of energy to the mechanism, train carried means for initially energizing said electro-responsive means, an electro-responsive clutch device for holding said energy applied to the mechanism, and a switch in circuit with said clutch device operable to open position by the locking movement of the lock bolt.

29. A railroad switch operating system comprising a switch operating mechanism, roadside devices controlling the operation of said mechanism to open and to close the switch, speed controlled train carried means cooperating with the roadside devices to close the switch and train carried means adapted to cooperate with the roadside devices to open the switch.

30. The combination of a railroad track, a siding, a switch, a ramp adjacent the track, a polarized electro-responsive device, a circuit including said ramp, said track and said electro-responsive device, the ramp being connected to one side of the electro-responsive device, a ramp adjacent the siding, and another circuit including the second ramp, the siding and the electro-responsive device, the second named ramp being connected to the other side of said electro-responsive device.

31. The combination recited in claim 30 and means carried by a forward car on a train adapted to impress an electro-motive force on the first circuit, and means carried by a rear car on a train adapted to impress an electro-motive force on the second circuit.

32. Signed at New York city in the county of New York and State of New York this 25th day of June, A. D. 1926.

ARCHIBALD G. SHAVER.
